Attest,

UNITED STATES PATENT OFFICE.

WILLIAM R. UHLEMANN, OF CHICAGO, ILLINOIS.

EYEGLASS-MOUNTING.

1,323,995.

Specification of Letters Patent. Patented Dec. 2, 1919.

Application filed February 8, 1919. Serial No. 275,708.

To all whom it may concern:

Be it known that I, WILLIAM R. UHLEMANN, a citizen of the United States of America, and a resident of Chicago, in the county of Cook, State of Illinois, have invented certain new and useful Improvements in Eyeglass-Mountings, of which the following is a specification.

This invention relates to eye-glass and 10 spectacle mounts in which the lens holding rings are formed of shell or like non-metallic material, and either wholly of such non-metallic material, or of a reinforced construction, and the present improvement 15 has for its objects:—

To provide a simple and effective structural formation and association of parts whereby the nose bridge of the mounting is attached to the non-metallic lens inclosing ring in a strong and substantial manner, and which admits of a close pupillarity of the lenses being attained regardless of the thickness of said non-metallic lens inclosing ring.

To provide a simple and compact formation and combination of the connecting means between the adjoining ends of a split non-metallic lens holding ring, affording a substantial attachment for the ring ends and 20 a like substantial attachment of the members of said connecting means, all as will hereinafter more fully appear.

In the accompanying drawing:—

Figure 1, is a perspective view showing the 35 general arrangement of parts of the present invention as applied to a pair of spectacles.

Fig. 2 is a detail vertical section illustrating the connecting means heretofore referred to.

Fig. 3 is a detail horizontal section illustrating the connection of the nose bridge to the lens holding rings.

Fig. 4 is a detail sectional elevation of a modified form of the connecting means 45 aforesaid.

Fig. 5 is a detail perspective view of the same.

Fig. 6 is a detail cross-section on line $\alpha-\alpha$, Fig. 4.

Like reference numerals indicate like parts 50 in the several views.

Referring to the drawing, 1 designates

the usual arch or bridge piece by which the lens holding members are fixedly connected together in properly spaced relation. 55

2 designates the pair of split lens holding members, which in the present construction are each formed of an outer ring of non-metallic material, such as tortoise shell, and an inner split metallic ring 3 acting as a reinforcement and grooved to receive the beveled margin of an eye-glass lens 4. Said inner ring 3 has a close fit in an annular groove formed in the ring 2, as shown and as usual in the present type of shell rim eye-glasses. 65

In the present improvement the ends of terminals of the lens engaging ring 3 at the split thereof, has outwardly disposed flanges or extensions 5 which when the ring 3 is contracted to engage the lens 4 in an assemblage of the parts, are in close contact to provide an extended and substantial abutment between the ring ends or terminals. 70

6 designates clip pieces or tongues extending in angular relation from the outer ends of the aforesaid flanges or extensions 5 and having approximately parallel relation to the main portion of the ring 3 and separated therefrom by a space corresponding to the thickness or cross-section of the non-metallic lens surrounding ring 2 as shown. 80

7 designate terminal prongs on the ends of the clip pieces 6 and adapted to be forced into recesses in the ring 2 to afford a simple 85 and substantial connection between the inner and outer lens holding members 2 and 3.

8 designate plate extensions or ears brazed or otherwise secured to the aforesaid bars or extensions 5 and extending outwardly beyond the same to receive fastening screws 9 by which the rings 3 are secured together in their contracted condition upon the lenses 4. 90

In the construction shown the plate extensions or ears 8 are formed with outer pivot ends for the pivotal connection of the temple bars 10 of a pair of eye-glasses or spectacles. 95

11 designates rebent end portions of the arch or bridge 1 connected to the rear of the lens holding rim 3 and continued forwardly in a curved form as an extension 12 adapted to embrace the outer surface of the non-me-

talic inclosing rim 2 and provide a rigid and substantial connection of the parts.

In the modified structure shown in Figs. 4, 5 and 6, the outer non-metallic ring 2 is of a square form in cross-section, but in other details the construction is substantially identical with that described above in connection with Figs. 1, 2 and 3. In such modified structure the ends of the clip pieces 6 are provided with lateral prongs 13 adjacent to the terminal prongs 7, with said prongs 13 adapted to be bent around the non-metallic ring 2 to embrace the same and afford increased stability to the parts required in some special eye-glass structures.

Having thus fully described my said invention what I claim as new and desire to secure by Letters Patent, is:—

1. In an eyeglass mounting, the combination of an outer split lens inclosing ring, an inner split lens holding ring arranged within said outer ring and having outwardly extending flanges on its ends forming abutments for the ends of the outer ring, said flanges having at their outer ends angularly

arranged clip tongues bearing against the outer face of the outer ring and provided with terminal prongs for engagement in recesses in said outer ring, and means for fastening said flanges together, substantially as set forth.

2. In an eyeglass mounting, the combination of an outer split lens inclosing ring, an inner split lens holding ring arranged within said outer ring and having outwardly extending flanges on its ends forming abutments for the ends of the outer ring, said flanges having at their outer ends angularly arranged clip tongues bearing against the outer face of the outer ring and provided with terminal prongs for engagement in recesses in said outer ring, plate metal members secured to said flanges and extending outwardly beyond the same, and fastening means extending through the outer ends of said plate members, substantially as set forth.

Signed at Chicago, Illinois, this 1st day of February, 1919.

WILLIAM R. UHLEMANN.
